UNITED STATES PATENT OFFICE.

EDWARD C. STEVENS, OF CINCINNATI, OHIO, ASSIGNOR TO THE DUTTENHOFER-
STEVENS COMPANY, OF CINCINNATI, OHIO, A CORPORATION OF OHIO.

DESIGN FOR A SHOE SOLE.

60,743.

Specification for Design. Patented Mar. 28, 1922.

Application filed November 5, 1921. Serial No. 513,189. Term of patent 14 years.

To all whom it may concern:

Be it known that I, EDWARD C. STEVENS, a citizen of the United States, residing at Cincinnati, in the county of Hamilton and State of Ohio, have invented a new, original, and ornamental Design for a Shoe Sole, of which the following is a specification, reference being had to the accompanying drawing, forming part thereof.

The figure is a perspective view of a portion of a shoe sole, embodying my design.

I claim:

The ornamental design for a shoe sole, as shown.

EDWARD C. STEVENS.
